UNITED STATES PATENT OFFICE.

ARTHUR ROGER, OF LYMM, ENGLAND.

WEFT-PILE-CUTTING MACHINE.

Application filed October 18, 1927, Serial No. 227,015, and in Great Britain November 2, 1926.

The invention relates to the cutting of weft pile fabrics, and has for object the provision of means of simple character in a machine for this purpose, said means consisting of drums 5 or the like from the one to the other of which the cloth is wound, in the one direction for cutting operations, and in the other direction for return of the cloth to the "setting-in" position of the cutting knife; in combination 10 with a cloth-tension control device consisting of pulleys or wheels connected to the drums, and in connection with each other by means of a flexible member or rope of continuous form provided with a depending loop, 15 said loop being weighted, or supporting what is known as a jockey pulley of sufficient weight or weighted for the purpose intended.

In the example herein described, gear 20 wheels are employed in the driving of the machine, but the jockey-pulley device is employed for controlling the tension of the cloth.

Referring to the drawings, Fig. 1 is a side 25 sectional elevation of portions of a weft pile cutting machine provided in accordance with a form of my said invention. Fig. 2 is a plan view of parts of Fig. 1, the cloth being removed, as well as the flexible connection shown in the last-named figure.

Fig. 3 is a side elevation of a modified 30 wheel for being connected by the flexible member named to another like wheel, and Fig. 4 is merely to indicate the nature of Fig. 3 when viewed from the front, said Fig. 35 4 being somewhat in diagram form only. Figs. 3 and 4 are on different scales to the previous figures.

Fig. 5 shows, on a reduced scale, a modification 40 of application of the jockey-pulley device.

Fig. 6 is a sectional view, on a different scale, of a portion of a drum about which the cloth is wound, with details relating to electrical disconnection, when required, or involved in such as stopping the machine.

A pair of drums are shown at *a*, revolvably mounted in the machine, and from one to the other of which drums the cloth is wound. 50 These drums are preferably light in character, consisting of rims and wire spokes, the latter after the manner of bicycle wheels, but on a large scale.

The drums *a* are here assumed to be driven from a main shaft *b*; through a known system of differential gearing indicated within 55 a casing *c*. The cross shafts of said gearing

are shown provided with worms *d* in gear with wheels *e* on the shafts carrying the drums *a*. Said worms are of suitable relative lead for driving the drums in the one or same 60 direction.

Thus for forward drive, the drums will rotate anticlockwise. The cloth wound about said drums is indicated at *g*, and the extreme 65 ends of said cloth are assumed to be in connection with the respective drums. For example, an end-part of cloth may be wrapped round a metal cross bar or "slide" to which bar, beyond the edges of said wrapped cloth, 70 are connected bands of metal or strong substance, the latter attached to the periphery or parts of the drum involved.

External tension and drag rollers about 75 which the cloth passes are indicated at *h*, *i*, *k*, by way of example.

When the machine or cloth is in the position suitable for the setting-in of the cutting knife indicated at 1 in Fig. 1, the knife end or guide point may be approximately below the position indicated by vertical arrow line 80 in Fig. 1, although the setting-in position need not be confined to such as referred to. This setting-in will take place when the greater portion of the length of cloth has been returned to the rear drum, or the drum 85 on the right in said Fig. 1, and after the motion of the machine has been reversed for so returning the cloth, or a new race of weft pile is in position for being cut.

In connection with the drums *a* through 90 the shafting carrying the same, are wheels *m* capable of turning with said shafting. These wheels have connected to them and wound about them, a flexible connection continuous from one wheel to the other, said connection being marked *n*. It is shown passing over guide and supporting rollers *o* assumed to be revolvably mounted on a fixed shaft *r* situated at some convenient position above the machine.

Said connection *n* is provided with a depending loop in which rests, in free manner, a jockey-pulley *s*. This pulley is shown to be weighted at its axis.

In operation, when the setting-in position 105 of the knife is reached, the loop of *n* with the jockey-pulley may be at the lowest position, and when the machine is in motion, in the forward direction, or the cloth is moving from right to left at the top side in Fig. 1, 110 and the connection *n* winds from the fore-wheel *m* on the left to the rear wheel on the

right, the loop aforesaid and jockey-pulley gradually lift a distance, and then reverse movement, or gradually fall; the reversal taking place about the time when both drums 5 have approximately equal amounts of cloth wound thereon.

In operation, the diameter of cloth on a drum obviously varies, but variation in tension of said cloth is controlled or prevented 10 by the jockey device named.

It will be seen that when the machine is not running and the jockey pulley *s* is motionless, then the weight of said pulley is tending to turn the drums *a* in opposite directions 15 or outwardly; but the cloth acting as a belt resists said movement, the normal tension of said cloth for this purpose being determined by the weight of said jockey pulley device.

20 If, however, at the time referred to the cloth is slack or tends to sag between the drums, the weight of the jockey pulley preponderates and said pulley falls until the normal tension is restored. The action is 25 here very similar to that of a chain weight in a well-known grand-father clock, said weight falling a little every time the escapement is released, but in this latter case the fall is uniform in extent, and in the case of the present 30 invention the fall is dependent upon the condition of the cloth tension at the time.

In similar manner, if, at the time first-referred to, the tension of the cloth exceeds the normal, due to its manufacture, for example, 35 then said tension preponderates, and an opposite action occurs, or the jockey pulley is lifted until normality is restored. When the machine is running, and the cloth tension remains normal, the cords *n* merely wind on 40 the one rim *m* and unwind from the other rim, as the case may be, but as the thickness of the wound cloth about the drums varies, and therefore the peripheral speeds of the rims *m* also vary, it will be seen that at some 45 part of the motion the jockey pulley is rising during the winding and unwinding operations, and falling at another part of said motion.

If, now, change of tension of the cloth occurs (say due to manufacture of the latter) 50 the compensating effect first-above described takes place, thus modifying or changing the direction of motion of the jockey pulley until normal tension is established.

55 For the sole purpose of tension control referred to, brakes are not required to be used additionally on the machine, since the contrary tendency of pull of the jockey pulley device upon the drums as compared with the 60 forward, or may be backward, drive of said drums, provides the requisite resistance upon the cloth and drums referred to.

In some cases it may be more convenient to 65 mount the jockey-pulley below the position of the machine, in which case the connection

n may be arranged relatively to wheels *m* after the manner indicated in Fig. 5; suitable guide pulleys being included.

It will be seen that the jockey pulley *s* ensures a weighted-loop in the cord *n*, said weighted loop bringing about the effect described as regards tension at the cloth.

In order to modify the distance of fall or movement of the pulley *s* modifications of wheels *m* may be adopted. In Figs. 3 and 4 75 for example a wheel in the form of what is known as a "fusee" is shown, or one having helical grooves for the connection *n*, said grooves being of reducing diameters. There would be a fusee for each wheel, and at the 80 setting-in position of the knife or machine the connection *n* would be about the smaller part of the fusee for the forward drum, and about the larger part of the fusee for the rear drum.

85 The means adopted for driving the machine forms no part of the present invention, or the means adopted for reversing the motion of said machine.

The direction of rotation of the drums is 90 determined by the direction of rotation of main shaft *b*.

95 But in those cases where electrical means are employed such as for stopping the machine brought about by the breaking of an electrical circuit, then the described method of making use of bars to which the cloth ends are attached or passed about the same, forms a convenient adjunct.

100 Thus in Fig. 6, the end portion of the cloth wound about the drum *a* or cloth carrier is assumed to be wrapped about a cross bar *t* the latter being attached to the drum by means of connecting bands such as *u* of thin metal, said bands being situated beyond the 105 side edges of the cloth *g*.

110 Under the conditions shown in Fig. 6 the bar *t* is pressed down by the cloth above the same wound round the drum, and said bar holds down one end of a lever *v* pivoted at *w* on drum *a*. The other leg of the lever *v* is thus kept in electrical contact with a plate *x* also attached to *a*. *v* and *x* are assumed to be in electrical circuit with the system employed by means of leads 1 and 2 respectively, which leads may pass down spokes of the drum *a* to the hub thereof, and along the latter to wherever desired.

115 When the cloth *g* unwinds sufficiently to move bar *t* away from lever *v* than spring *z*, connecting *v* with the rim of drum *a* operates to break the contact between *v* and *x* as will be understood. An insulated stop is shown at 3 attached to the rim of drum *a* aforesaid.

120 I claim:—

1. In a machine employed for cutting the pile of weft pile fabrics, a pair of revolubly mounted drums from the one to the other of which said cloth is wound, in the one direction for pile cutting operations, and in the 130

other direction for bringing the cloth to the position suitable for the setting-in of the cutting knife, rims connected to said drums in connection with each other by means of a 5 flexible member capable of being wound about the same in opposite directions, a weighted depending loop in said connection, and operating through said connection rims and drums for maintaining the tension of 10 said cloth constant, substantially as herein set forth.

2. In a machine employed for cutting the pile of weft pile fabrics, a pair of revolubly mounted drums from the one to the other of 15 which the cloth is wound, in the one direc-

tion for pile cutting operations, and in the other direction for bringing the cloth in position for the setting-in of the cutting knife, wheels connected to said drums in connection with each other by means of a flexible rope 20 capable of being wound about said wheels in opposite directions, a depending loop in said connection, a jockey pulley freely riding on said loop, and operating through said connection, wheels and drums for maintaining 25 the cloth in constant tension, substantially as herein set forth.

In testimony whereof I have affixed my signature.

ARTHUR ROGER.
